(57) **CLAIM**

The ornamental design for a display screen with animated graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen with animated graphical user interface showing a first image in the sequence showing our new design;

FIG. 2 is a second image thereof;

FIG. 3 is a third image thereof;

FIG. 4 is a rear view of a portable device incorporating a display screen with animated graphical user interface as shown in FIGS. 1-3;

FIG. 5 is the left side view thereof;

FIG. 6 is the right side view thereof;

FIG. 7 is the top view thereof; and,

FIG. 8 is the bottom view thereof.

The broken lines around FIGS. 1-8 show a display screen thereof and form no part of the claimed design. The broken lines within FIGS. 1-8 show unclaimed portions of the animated graphical user interface and graphical user interface and form no part of the claimed design.

The appearance of the animated images sequentially transitions between the images shown in FIGS. 1-3. The process or period in which one image transitions to another forms no part of the claimed design.
